UNITED STATES PATENT OFFICE.

JOSEPH ANDERSON SCHERMERHORN, OF TRENTON, NEW JERSEY, ASSIGNOR TO E. H. FREEMAN ELECTRIC COMPANY, OF TRENTON, NEW JERSEY, A CORPORATION OF NEW JERSEY.

LIGHTNING ARRESTER.

Application filed August 17, 1922. Serial No. 582,435.

To all whom it may concern:

Be it known that I, JOSEPH A. SCHERMERHORN, citizen of the United States, residing at Trenton, in the county of Mercer and 5 State of New Jersey, have invented certain new and useful Improvements in Lightning Arresters, of which the following is a specification.

This invention relates to an improvement 10 in lightning arresters and has special reference to an arrester especially adapted for use in radio installations.

A primary object of the invention is to provide a simple, practical, reliable and safe 15 device that will fully meet underwriters' requirements and also making a good ground connection. To that end the invention contemplates a device that may be economically manufactured and readily assembled and 20 which when installed for use will adequately take care of the lightning discharges of small as well as large voltage.

A further object of the invention is to provide a completely encased and weatherproof 25 device wherein one of the electrodes is adjustable thereby to compensate for variation in the manufacture of parts and insure their being brought into proper operative 30 relation when the device is installed for use.

With the above and other objects in view 35 which will more readily appear as the nature of the invention is better understood, the same consists in the novel construction, combination and arrangement of parts herein- 40 after more fully described, illustrated and claimed.

A preferred and practical embodiment of the invention is shown in the accompanying drawings, in which:

40 Figure 1 is an elevation of the improved device.

Figure 2 is a vertical sectional view thereof.

45 Figure 3 is an interior plan view of the base section of the casing.

Figure 4 is an interior plan view of the cap section.

Similar reference characters designate corresponding parts throughout the several 50 figures of the drawings.

Although it will of course be understood that the invention is susceptible of embodiment in various designs and structural forms, nevertheless the distinguishing features and characteristics thereof always con-

sist of a weatherproof casing designated generally as A and providing an interior chamber B which houses the electrodes C and D, one of which is adjustable with relation to the other thereby to insure the proper contact 60 of the parts when the device is assembled for use. In that way any variation in the manufacture of the sections of the insulating casing A or the electrodes and their associated parts may be adequately compensated 65 for in a simple and practical manner.

Referring now more particularly to the details of the arrangement shown in the drawings it will be observed that the casing A preferably consists of the mating sections 1 70 and 2, the latter being provided with an up-standing threaded portion 3 for fitting into the interiorly threaded flange 4 of the section 1. The said section 2 constitutes a body or base section while the opposite section 75 25 functions as a cap although it will of course be understood that the designations of these members by such terms in no way limits the installation or use of the invention to the position illustrated in the drawing. 80

The base section 2 is provided with a chamber 5 having the side wall thereof provided with the offset centering ribs 6, and, as shown in Figures 2 and 3 the bottom of this chamber may be provided with vent 85 ports 7 for establishing communication between the interior of the casing and the outside air to permit of sufficient circulation to prevent condensation or the collection of moisture which would interfere with the 90 proper functioning of the electrodes.

The cap section 1 is preferably formed with a chamber 8, the wall of which is recessed to receive a feed nut 11 for the conductor rod 12 of the electrode unit C whereby 95 the said rod 12 may be shifted longitudinally by turning the same in the nut thereby to move the electrode unit C toward the unit D after the casing sections are assembled to bring the electrode units into proper relation. 100

The electrode units C and D are of similar construction, and each consists of a metallic shell or thimble 13 provided with an out-turned flange 14 and carrying therein a 105 carbon disk 15 which may be conveniently held in place by punching or otherwise deflecting the sides of the thimble inwardly as indicated at 16. As will be observed from the drawings the exposed faces 17 of the car- 110

- bon disks project beyond the flanges 14 thereby to engage with and securely clamp an insulating plate or sheet 18 of mica or the like between the carbons of the opposite electrodes. As shown, this said mica plate 18 is provided with an opening 19 and is of the same diameter as the flanged portion of the thimble, thereby being entirely coextensive with the portions of the electrodes which face each other. By this arrangement it will be seen from Figure 2 that the carbon inserts 15 are intended to be in close contacting relation with the mica plate, and by reason of the projection of the carbons beyond the open ends of the thimble, the flanges 14 are spaced apart while the periphery of the mica plate projecting beyond the carbon disks provides an insulation barrier between the faces of the flanges 14.
20. Because of the above arrangement of the mica plate electrical currents of small voltage (less than 500 volts) will pass from one carbon to the other through the opening 19, while currents of large voltage will pass between the edges of the flanges 14, thereby fully meeting underwriters' requirements in that respect. It will therefore be apparent that with the construction and arrangement described the electrode units C and D adequately provide for safely handling currents of low voltage as well as currents of high voltage, preferably arresting the latter in a safe and practical way.
- As previously indicated the electrode unit 35 C is carried by the threaded conductor rod 12 which works in the threaded nut 11 to adjust the position of the unit C with reference to the unit D; and, for the purpose of locking the conductor rod 12 in the position, the portion thereof which projects beyond the outside of the cap 1 may be provided with a washer 21 and lock-nut 22 with which the binding nut 23 may cooperate in the usual manner to clamp the terminal wire or its equivalent to the conductor rod. The portion of the cap 1 through which the conductor rod passes may be recessed as at 24 and filled with a suitable filler such as cement or putty thereby to make 40 a water-tight joint between the washer 21 and the cap.
- The electrode unit D is carried by the conductor 12^a, which, like the rod 12 is provided with a flanged head α that is 45 clamped between the ends of the thimble 13 and the carbon disk or insert 15, while the portion of the conductor rod which projects beyond the base 2 carries the usual lock-nut 22^a and binding nut 23^a.
50. In assembling the device for use the electrode unit D is placed in a fixed or stationary position in the base and the mica plate 18 is preferably centered on the face of the carbon by the centering rib 6. The cap section 1 may be then fitted to the base by screwing

the interiorly threaded flange 4 thereof onto the threaded portion 3 of the base and the conductor rod 12 may be rotated in the nut 11 until the carbon of the electrode unit C firmly engages with the mica plate. 70 The sealing medium may thereafter be placed in the recess 24 of the cap 1 and the washer 21 and lock-nut 22 then placed in position. When the device is thus assembled it is ready for installation by simply connecting the binding nuts 23 and 23^a with the proper terminals.

Without further description it is thought that the features and advantages of the invention will be readily apparent to those skilled in the art and it will of course be understood that changes in the form, proportion and minor details of construction may be resorted to without departing from the spirit of the invention or scope of the appended claims.

I claim:—

1. A lightning arrester including a pair of cup-like insulating casing sections having interfitting mating open end portions, electrodes carried by said sections and housed therein, said electrodes including carbon disks and metallic thimbles carried by the disks.

2. A lightning arrester including a casing 95 consisting of separable complementary sections, electrode units carried by said sections, and means for shifting one electrode with reference to the other.

3. A lightning arrester including hollow 100 detachably connected complementary sections providing an interior electrode chamber, an electrode unit carried by each section and arranged within the chamber, and means for bringing said sections into operative 105 relation independently of the position of the casing parts.

4. A lightning arrester including a chambered base section having a threaded flange, a chambered cap section having an interiorly 110 threaded portion for receiving said flange, an electrode unit rigidly carried by the base and a cooperating electrode unit adjustably carried by the cap whereby the electrodes may be brought into operative relation independently of the cap and base. 115

5. A lightning arrester including a base section, an electrode rigidly mounted therein, a cap section detachably fitted to the base, and an electrode adjustably carried by the cap, said electrode including a conductor member movably mounted in the cap to be shifted in the direction of its axis. 120

6. A lightning arrester including a base section, a stationary electrode mounted 125 therein, a cap section detachably fitted to the base, and an electrode adjustably carried by the cap, said electrode member including a threaded conductor rod, a nut carried in the cap and receiving said threaded 130

conductor rod thereby to shift said electrode unit with reference to the stationary electrode carried by the base.

7. A lightning arrester including mating 5 casing sections, opposite electrode units carried by said sections and each unit consisting of a metallic thimble and a carbon disk therein and projecting beyond the open end thereof, and an insulating plate adapted to 10 be arranged between the carbons of the opposite electrodes and providing an insulation barrier between the spaced edges of said thimbles.

8. A lightning arrester including mating 15 casing sections, electrode units carried by said sections and each unit consisting of a metallic thimble having an offset terminal flange at its open end, a carbon disk arranged within the thimble and projecting 20 beyond the face of its flange, and a perforated insulating plate clamped between the carbons and the peripheral edge of said plate extending beyond the carbons and providing an insulation barrier between the 25 spaced flanges of the thimbles.

9. A lightning arrester including a base section formed with a chamber and having a vent port and centering ribs formed within the chamber, an electrode unit arranged in 30 a fixed position within the chamber of the base, a cap section adapted to detachably engage the base, an electrode unit carried thereby, and an insulating plate adapted to be centered by the ribs in the chamber of 35 the base and clamped between the electrode units carried by the cap and the base.

10. In a lightning arrester, a casing section, an electrode unit carried by said section, said electrode unit comprising a metal- 40 lic thimble, a conductor rod having a

flanged head engaging with one wall of the thimble, a carbon disk secured in the open end of the thimble to clamp the flanged head against the end wall of the thimble, means for locking said conductor rod to the casing 45 and a binding nut carried by the conductor rod.

11. In a lightning arrester, a casing member, an electrode carried thereby, said electrode including a metallic thimble, a conductor rod connected to said thimble, means for adjustably connecting said rod with the casing, means for locking the rod in adjusted position, means for sealing the opening in the casing through which the conductor rod projects, and a binding nut carried by said conductor rod.

12. A lightning arrester including spaced metallic thimbles, a carbon disk in each thimble and projecting beyond the open end 60 thereof and an insulating plate arranged between the opposite carbons and projecting between the spaced edges of the thimbles.

13. In a lightning arrester, oppositely arranged metallic electrode thimbles spaced 65 apart at their edges, a carbon element fitted in each thimble and having a locked engagement therewith, and an insulator disposed between the spaced edges of the metallic thimbles.

14. In a lightning arrester, oppositely arranged metallic thimbles spaced apart at their edges and each carrying a carbon disk projecting beyond the open end thereof, and adjusting means for one of said thimbles 75 and the carbon carried thereby.

In testimony whereof I hereunto affix my signature.

JOSEPH ANDERSON SCHERMERHORN.
